William Slavery designed of J. H. Bonklin (A) and Son's
No. 1
ctd. 205
Dated Nov. 29, 1848.

Des. 205

Wm Savery joint inventor with and assist^d by
Conklin City of New York U.S. Letters Patent No. 205
dated Nov. 28. 1848.

Specification

The schedule referred to in these letters Patent and
making part of the same. —

To all whom it may concern: Be it known that William
Savery and James H. Conklin of the City County and
State of New York, have invented or produced a new
useful and ornamental design for an oven mouth
or front embracing a variety of new and ornamental
figures and mouldings on said front combined
in one. And we do hereby declare the following is
a full and exact description of the same, referred
being had to the annexed drawing making a part
of this specification.

Letter A of drawing No. 1 represents the frame
of the front. —

Letter B. of drawing No. 1 represents the door
of the front.

What we claim and wish to secure by
Letters patent as original with us is the original
